UNITED STATES PATENT OFFICE

109,296

DESIGN FOR A DISH OR SIMILAR ARTICLE

William H. Gerth, New York, and Grosvenor N. Allen and Charles A. Bennett, Oneida, N. Y., assignors to Oneida Ltd., Oneida, N. Y., a corporation of New York

Application February 15, 1938, Serial No. 75,132

Term of patent 14 years

To all whom it may concern:

Be it known that we, William H. Gerth, a citizen of the United States, residing at New York city, county and State of New York, and Grosvenor N. Allen and Charles A. Bennett, both citizens of the United States, residing at Oneida, county of Madison, State of New York, have invented a new, original, and ornamental Design for a Dish or Similar Article, of which the following is a specification, reference being had to the accompanying drawing, forming a part of the same, in which—

The essential feature of our new design is the ornamental figures extending around the face of the dish but shown only for a portion thereof in the drawing.

We claim:

The ornamental design for a dish or similar article, as shown and described.
